(57) **CLAIM**

The ornamental design for a ice tongs, as shown and described.

DESCRIPTION

FIG. 1 is a perspective view of the ice tongs showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front sectional view thereof taken along line 8-8 of FIG. 6.

All of the material from the Danish reference, which is essential to the claimed design is included in this application. Any material in the Danish reference, which is not present in this application forms no part of the claimed design.

1 Claim, 8 Drawing Sheets
